UNITED STATES PATENT OFFICE.

JOHN C. DEAGAN, OF CHICAGO, ILLINOIS.

APPARATUS FOR TUNING MUSICAL INSTRUMENTS.

1,402,219.

Specification of Letters Patent.

Patented Jan. 3, 1922.

Original application filed August 6, 1917, Serial No. 184,584. Divided and this application filed May 14, 1920. Serial No. 381,264.

To all whom it may concern:

Be it known that I, JOHN C. DEAGAN, citizen of the United States, residing at Chicago, in the county of Cook and State of Illinois, have invented a certain new and useful Improvement in Apparatus for Tuning Musical Instruments, of which the following is a full, clear, concise, and exact description.

10 My invention relates to apparatus for tuning musical instruments, being a division of my original application Serial No. 184,584, filed August 6, 1917, in which original application I have claimed the method of 15 tuning herein disclosed.

In practicing the method of the invention the tone of master pitch is produced and the instrument is tuned to cause it to produce a similar tone with a pitch as nearly in unison 20 therewith as possible, whereafter a testing tone similar to the tone of master pitch and the tone of the instrument being tuned but differing in pitch one, two, three, or more vibrations per second from the pitch of the 25 master tone, is concurrently produced with the adjusted tone of the musical instrument, the tone of master pitch being in the meantime silenced. If the testing tone differs one vibration from the tone of master pitch 30 then the adjusted tone of the musical instrument being tuned should, to prove its accuracy, combine with the testing tone to produce one beat per second which is producible by such master and testing tones. If it takes 35 longer than a second to produce a beat then the adjusted tone is too flat and if it takes less than a second to produce a beat then the adjusted tone is too sharp and the musical instrument is adjusted until the adjusted 40 tone, in combination with the testing tone, produces one beat per second. If the testing tone differs two vibrations from the tone of master pitch then the adjusted tone should, to prove its accuracy, combine with the testing tone to produce two beats per second, 45 and so on.

The instrument of my invention comprises a plurality of sound producing metallic solid bars one of which serves to produce a tone 50 of selected master pitch and another of which produces a testing tone similar to but slightly differing in pitch from the tone of master pitch. There is desirably a plurality of bars for producing testing tones that differ in pitch from each other as well as from

the tone of master pitch. Sound dampers are preferably provided, one individual to each bar whereby the bars may be prevented from vibrating in sympathy with sounded bars and whereby bars which are sounded 60 may be silenced. There is also provided a timing device for timing the beats jointly produced by the testing tone and the adjusted tone of the musical instrument that is being tuned.

I will explain my invention more fully by reference to the accompanying drawings showing the preferred form of instrument with the aid of which the method of my invention may be practiced and in which drawings Fig. 1 is a front view of the instrument with the front cover of the casing removed, a part broken away; Fig. 2 is a sectional view on line 2—2 of Fig. 1 with the cover of the casing closed; Fig. 3 is a 70 view on line 3—3 of Fig. 1; Fig. 4 is a view on line 4—4 of Fig. 2; and Fig. 5 is a view on line 5—5 of Fig. 4.

Like parts are indicated by similar characters of reference throughout the different 80 figures.

The sound producing elements are preferably in the form of vertically hung vibrant solid metallic bars that are to be struck by a hammer to set them in vibration. Bars 85 1 and 2 are respectively capable of producing tone A having the international pitch of four hundred and thirty five vibrations per second and the orchestral pitch of four hundred and forty vibrations per second. In 90 succession between bars 1 and 2 I preferably provide bars 3, 4, 5 and 6 respectively producing tone A having pitches of four hundred and thirty six vibrations, four hundred and thirty seven vibrations, four hundred and thirty eight vibrations, and four hundred and thirty nine vibrations per second. These bars are suspended at nodal points upon the shanks of screws 7 projecting forwardly from a support 8 that is located 95 within the cabinet 9. These bars are permitted to swing but are limited in their forward and backward movements by means of strips 10 upon the screws 11, and the cushions 12 upon the support 8. The tuning pendulum 15 is swung at the lower end of a chain 16 attached at 17 to the cabinet, the purpose of which is to time the beats jointly produced by the testing tone and the adjusted tone of the musical instrument 110.

that is being tuned. This pendulum preferably completes a swing once a second and ticks at the conclusion of each swing.

When any two bars immediately adjacent are concurrently set into vibration beats will arise with a frequency of one beat per second. If the vibrating bars are separated by one bar two beats per second will arise. If the vibrating bars are separated by two bars three beats will result, and so on. In order to accentuate the beats, resonators 18 may be provided behind the bars.

In tuning his musical instrument by the testing instrument as shown, the musician sets that bar into vibration (say bar 1) which will produce tone A of selected or master pitch and will cause his musical instrument *m* to sound a tone as nearly in unison with the tone of master pitch as possible, whereafter the sounded bar of selected or master pitch is silenced and any other bar (being then a testing bar) is sounded concurrently with the sounding of the adjusted tone A of the instrument being tuned. If, for example, the selected testing bar is bar 6, it should combine with the adjusted tone A of the instrument being tuned to produce exactly four beats per second. If two bars intervene between the bar of master pitch and the testing bar, the adjusted tone should combine with the testing tone to produce three beats per second, and so on.

To silence the bar producing the tone of master pitch and to silence the other bars also, I provide damper 19 for each bar and means individual to each damper for maintaining it in silencing engagement with the bar pertaining thereto. Not only may the bar of selected pitch be silenced by its damper, but the other dampers prevent their bars from sounding in sympathy with any vibrating bar and the tone of the musical

instrument that is being adjusted. In the arrangement illustrated, each damper is 45 mounted in the cupped upper end of a sleeve 20 mounted to move vertically upon the guiding sleeve 21. A spring 22 is bottomed upon a pin 23 and has its upper end in pressing engagement with a bayonet pin 24 50 which is fixed with respect to the movable sleeve 20. This pin operates in bayonet slots 25 in the fixed sleeve 21. By imparting suitable vertical and rotary movements to a sleeve 20, the corresponding damper 55 may be maintained in or out of engagement with its bar, the spring 22 being adapted to hold its damper against the lower end of the corresponding bar.

As as hitherto been stated the sounding 60 bars are of solid metal to produce clear and definite tones, being in this respect superior to vibrating pipes and tuning forks. Moreover, the vibrations of these bars are not affected by the weather and the handling 65 thereof will not throw them out of tune. The bars are made more perfectly to perform their functions by suspending them at their upper nodal points and having them normally free of contact elsewhere. 70

Having thus described my invention I claim as new and desire to secure by Letters Patent the following:—

In an instrument employed in tuning musical instruments, the combination with 75 solid metallic bars tuned to produce tones of nearly the same pitch, of dampers for said bars, means individual to each damper constantly tending to maintain it in silencing engagement with the related bar, and 80 means individual to each damper for releasably locking it out of engagement with the related bar.

In witness whereof, I hereunto subscribe my name this 25th day of March, A. D. 1920. 85

JOHN C. DEAGAN.
